(57) **CLAIM**

The ornamental design for a head up display, as shown and described.

DESCRIPTION

FIG. 1 is a front and top perspective view of a head up display, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated in FIG. 2. The dash-dash broken lines illustrate portions of the article that form no part of the claimed design. The dash-dot-dash broken lines, in FIG. 2 and FIG. 9, depict boundary lines and enlarged views, which form no part of the claimed design.

1 Claim, 9 Drawing Sheets
